UNITED STATES PATENT OFFICE.

UMBERTO M. CERVELLO, OF SPOKANE, WASHINGTON, ASSIGNOR OF TWO-FIFTHS TO
CHESTER L. LEHMANN, OF SPOKANE, WASHINGTON.

CONCRETE-REINFORCING STRUCTURE.

1,161,112.

Specification of Letters Patent. Patented Nov. 23, 1915.

Application filed January 19, 1915. Serial No. 3,063.

To all whom it may concern:

Be it known that I, UMBERTO M. CERVELLO, a citizen of the United States, residing at Spokane, in the county of Spokane 5 and State of Washington, have invented certain new and useful Improvements in Concrete-Reinforcing Structures, of which the following is a specification.

This invention relates to improvements in reinforcing structures for use in the formation of columns, beams, floor slabs and other structural parts formed of concrete, which usually consist of a plurality of reinforcing bars each provided with a series of reinforcing rodlike elements, the latter sometimes taking the form of stirrups.

One of the principal objects of my invention is to provide a novel means of securing the so called stirrups to their bars in such a manner that the stirrups will be held in fixed or predetermined relation with respect to said bars.

Bars of this type have usually been provided with a flange or web in which an opening has been formed through which the stirrup could be projected into position, and one of the features of my invention consists in displacing the material adjacent the opening in such a manner as to change the form of the latter, from its original contour, so as to cause one or more portions of the margins of the opening to engage the stirrup and lock the latter in position.

A further feature consists in providing such opening with a circular portion so that the opening can be formed sufficiently close to the edge of the web or flange as to weaken the latter and thereby facilitate displacement or distortion of the web for the purpose of engaging portions of the margin of the opening with the stirrup to lock the latter in position.

A still further object is to provide an opening formed in part of circular and polygonal portions, in combination with a stirrup of polygonal cross-section, so that the polygonal portion will coact with the subsequently distorted portion to lock the stirrup in position.

Further objects of the invention will be more fully described in connection with the accompanying drawings and will be more particularly set forth in and by the appended claims.

In the drawings:—Figure 1, is a view in side elevation of a reinforcing bar with a plurality of stirrups secured thereto in accordance with my invention. Fig 2, is a sectional view taken on line 2—2 of Fig. 1. Fig. 3, is an enlarged side elevation of a portion of the reinforcing bar with one stirrup in position and the adjacent stirrup omitted. Fig. 4, is a cross sectional view of a column equipped with the device of my invention. Fig. 5, is a sectional view showing my invention applied to a building structure with the columns and beams in elevation and the floor slabs in section. Fig. 6, shows the invention applied to a footing with reinforcements disposed in angular relation.

Like characters of reference designate similar parts throughout the different figures of the drawings.

My invention includes a reinforcing bar 1, having a body portion which may be substantially cylindrical in form, and provided with a projecting flange or web 2. Associated with the reinforcing bar is a plurality of rod-like reinforcing elements which are usually in the form of stirrups and which are shown in this form as indicated at 3. It is necessary to maintain the stirrups and bar in substantially fixed relation with respect to each other, so that they will retain the desired relative relation with respect to each other when the concrete body is being formed or molded about the same. The web 2 is shown provided with a plurality of openings 4 which are equi-distant in space at suitable distances apart lengthwise of the web 2, and the stirrups are extended or projected through said opening.

One utility of my invention is illustrated in Fig. 5, wherein a floor slab 5 is reinforced with the device of my invention, the stirrups 3 being relatively short. A floor beam is indicated at 6 and the reinforcing bar 1 with relatively longer stirrups 3, are shown in dotted lines, embedded in the beams in the selected manner desired to reinforce the same. At the ends of the beam 6, the stirrups 3 extend into the columns 7.

In Fig. 6, a footing 8 is shown in which the reinforcements extend in transverse relation.

As applied to a column, as indicated in Fig. 4, the reinforcing rods 1 will be dis-

posed upright with the webs 2 thereof projecting radially from the body portions of the bars. A reinforcing element in the form of a wire 9, which is rolled or otherwise shaped to form a cylinder, the wire being also formed spirally and strung through the openings in the webs 2.

The foregoing structures are examples of the various utilities of my invention, and I will now describe that portion of the structure which comprises the novelty of the invention, reference being made more particularly to Figs. 1, 2 and 3.

The openings 4 are of a given cross section or contour, which is different from the cross section of the stirrups 3. As shown, the stirrups 3 are square in cross section and the openings 4 are formed in part of polygonal and circular portions 10 and 11, respectively. 15 The polygonal portion comprises angularly disposed portions which meet to dispose their apex 12, nearest the body portion of the bar 1. The circular portion 11 is disposed nearest the edge 13, of the web 2, and 20 in the present construction, the parts are so proportioned that the opening will be formed in a manner to materially weaken that part of the material 14, of the web 2, adjacent the opening 4. This feature will 25 not be carried to the extent that there will be any danger of the stock of the web 2 being broken or ruptured when the hole or opening 4 is formed or punched, however, the reduction of stock adjacent the opening 30 will be so reduced as to facilitate an important manipulation thereof which will now be described.

When the stirrup is in position, its upper sides will coact with the angular portions of 40 the opening and fit thereagainst. In order to anchor the stirrup in position, I distort or displace material of the web adjacent the opening 4, as indicated at 15, in such a manner as to change the circular portion 11, or 45 a part thereof into a contour of polygonal formation, as indicated at 16, and which will be so shaped as to conform to and engage the lower corner 17, of the stirrup. Thus it will be seen that this distortion of material 50 will function in coacting relation with the angular portions 10, at opposite points with respect to the polygonal stirrup 3, to securely anchor the latter in predetermined relation with respect to the bar 1. In the 55 most preferred construction, the distortion 15 is effected by operation upon the edge 13, as indicated at 18, in such a manner as to roughen said edge to more intimately embed the same in the concrete. It will thus be 60 seen that I employ a stirrup of one cross section and an opening having a contour different from the cross section of the stirrup, the opening having its margins distorted to conform to and coact against the faces of 65 the stirrup.

While I have herein shown and described specific forms of my invention, I do not wish to be limited thereto except for such limitations as the claims may import.

I claim:—

1. In a reinforcing structure, a reinforcing bar provided with a web having an opening in the latter of a given cross-section, and a reinforcing rod extending through such opening and having a cross-section different in form with respect to the cross-section of said opening, the material of the web adjacent said opening being deformed to change the original contour of said opening and engage portions of the margins of 80 said opening against peripheral portions of that portion of the rod disposed in said opening to lock said rod against movement in said opening, substantially as described.

2. In a reinforcing structure, a reinforcing bar having a web provided with an opening therein having a first portion of one contour and a second portion of a different contour from said first portion, and a reinforcing rod of a cross-section corresponding to and having certain portions of its periphery fitting in and against said first portion of said opening, the material adjacent the said second portion of said opening being distorted to change said 95 second contour portion of said opening from its original form to a form corresponding to and to engage such changed portion of said opening against said rod, substantially as described.

3. In a reinforcing structure, a reinforcing bar provided with a web having an opening formed in part of circular and polygonal portions with the circular portion adjacent the edge of the web and sufficiently close to said edge to weaken the latter adjacent said opening, and a rod of polygonal cross-section extending through said opening and having a portion of its periphery fitting in and engaging the polygonal part of said opening, the material along said weakened edge portion being distorted to change the form of said circular part of said opening to a polygonal form and force such changed parts against 110 said rod in opposition to the originally formed polygonal part of said opening to hold said rod in predetermined relation with respect to said bar, substantially as described.

4. In a reinforcing structure, a reinforcing bar provided with a web having an opening formed in part of angular portions meeting to dispose the apex of such angular portion nearest the body of said bar, the remaining part of said opening being circular and being nearest the edge of said web, and a stirrup of square cross-section having its bight disposed in said opening with one corner of said bight nearest said 125 130

edge of said web, the material of the web being displaced to change a portion of the circular part of said opening to conform to and fit against the sides of said last named corner portion thereby locking said stirrup in fixed relation with respect to said bar, substantially as described.

In testimony whereof I affix my signature in presence of two witnesses.

UMBERTO M. CERVELLO.
